UNITED STATES PATENT OFFICE.

HARRIET R. TRACY, OF NEW YORK, N. Y.

FIRE-ESCAPE.

SPECIFICATION forming part of Letters Patent No. 272,103, dated February 13, 1883.

Application filed June 30, 1882. (No model.)

To all whom it may concern:

Be it known that I, HARRIET R. TRACY, of the city, county, and State of New York, have invented certain new and useful Improvements 5 in Fire-Escapes, of which the following is a clear, full, and exact description of the same, reference being had to the accompanying drawings, and to the reference-letters marked thereon.

10 The object of my invention is to produce a simple, cheap, durable, compact, and efficient fire-escape ladder, which may be folded into a small compass, be easily and readily dropped into position for use, and which will afford a 15 protected and fire-proof stairway upon which persons may enter and descend conveniently, and without danger or accident, also affording at the same time suitable means for enabling firemen to reach the upper stories of the burning 20 building without interfering with the descent of persons.

My invention consists in the use of a flexible fire-proof trough provided with interior and exterior steps, which also serve as braces.

25 Referring to the drawings, Figure I is a sectional elevation of a building, showing my improved fire-escape attached to one story of a building and thrown out for use; also showing, again, my improved fire-escape attached to another story of building, folded up ready for use. Fig. II is a detached sectional view of 30 my improved fire-escape. Fig. III is a view showing my improved fire-escape attached to a portable box to enable it to be carried from place to place; Fig. IV, detached front view of the escape.

A represents an aperture in the wall of a building, B', of sufficient size to accommodate the fire-escape when folded up. This aperture 40 is intended to be furnished with an outside door or shutter of iron, B, and an inside door, C. The outside door is preferably hinged at the bottom, so that when released from the interior of the building, it will open automatically; but it may be hinged in any other desirable way. The inside door may be of any 45 style or material, and hinged in any suitable way, so that it can be readily opened. The aperture should be so located as that it 50 will be readily accessible from the floor. To the interior of the aperture A is fastened one

end of flexible canvas D, in any suitable manner. The sides of the canvas are supported by a number of metallic strips, E, hinged one to the other. The number of these metallic 55 strips correspond with the number of steps required to reach the ground, for these strips, so placed against the canvas, cause the same to shape itself into steps G of convenient size, and accessible from the interior of said canvas, 60 which is formed into a trough-shape. (See Figs. II and IV.) Along the upper edges, e e, of the canvas trough is fastened a number of cross-bars, F, which serve to hold the trough open, and at the same time act as an outer 65 ladder for firemen to ascend. These cross-bars may be fastened to the trough in any other suitable manner. These cross-pieces F also serve as hand-pieces for persons descending the steps G. If so desired, the bottom 70 of the steps G may be provided with cross-bars to present a firmer bottom to step upon.

When the escape is not in use it is folded up and placed in the aperture A, (see Fig. I at P,) or within the portable-box G'. (See Fig. 75 III.) The object of placing the escape within said box is that it can be moved from room to room. When the escape is placed within the box G it is provided with a rod at one end, by which it is fastened to the window-casing, as 80 the escape is always thrown out of the window when not fastened into an aperture, A, in the wall of a building.

To use my fire-escape it is only necessary to open the inner door of the aperture, unlatch 85 the outer door, and thrust the top of the pile out. Persons below will take hold of the bottom ropes, H, fastened to the lower end of the canvas trough D and draw the escape from the building and make it assume a proper inclination to enable persons to descend. The canvas portion of the escape will be coated or 90 saturated with any of the usual fireproofing compounds.

By constructing a fire-escape as above described greater safety is obtained, for the persons descending are prevented from falling by the side walls, m, of the trough D, and steadied in descending by the cross-pieces.

Having thus described my invention, I desire to claim—

1. The flexible fire-proof canvas trough D,

with steps G, substantially as and for the purpose set forth.

2. The flexible fire-proof canvas trough D, with steps G, in combination with metallic strips E and cross-pieces F, substantially as and for the purpose set forth.

3. The flexible fire-proof canvas trough D, with steps G, metallic strips E, cross-pieces F, and stay-ropes H, in combination with building-aperture A, or movable or portable box G', substantially as and for the purpose set forth.

4. In a fire-escape, the flexible fire-proof canvas trough D, provided with steps G, metallic strips E, cross-pieces F, and stay-ropes H, secured to aperture A, provided with outside 15 and inside doors, or to window-casing, substantially as and for the purpose set forth.

HARRIET R. TRACY.
